VERTICALLY SHIFTABLE PLATFORM SUPPORT FOR OFFICE FURNITURE

Frank Stanley Schade, Holyoke, Mass., assignor to National Blank Book Company, Holyoke, Mass., a corporation of Massachusetts

Application March 21, 1950, Serial No. 150,924

1 Claim. (Cl. 311—39)

1

This invention relates to a vertically shiftable platform support for office furniture such as a tray support for an office work stand of the type adapted for holding and handling bulky record files.

Large business and governmental offices usually have various types of voluminous and bulky records for a variety of bookkeeping transactions, personnel dispositions or administrative regulations, and the like. Such records are kept systematically indexed and classified and generally for handling purposes are stored in such a way that a group of records may be removed from the location of storage to be carried to a work location where entries can be made or the record sheets otherwise referred to. In many filing systems the records may be permanently stored in portable trays of various types and in other systems groups of files may be assembled from their permanent locations on carrying trays and transported to a working station as near a desk or other working area. It is also common in working with such files for an office worker to alternately stand and sit for certain periods while referring to the record sheets in the files. An object of this invention is to provide a device to assist in expediting the handling of this type of office work.

To illustrate more specifically, a clerk may be working at his desk with a particular set of records. The records may be held on a work stand or other movable support near the desk at a convenient height. Having completed the desk work, the clerk then finds it necessary to do reference or tabulating work with the same set of records at filing cabinets. For efficient handling the records should then be at a different height on the stand for reference and checking at a convenient reading level or for making appropriate entries. The device of this invention is accordingly designed to provide a readily adjustable mechanism to accomplish a change in working level with a minimum of inconvenience and effort. It is easily manipulated to raise or lower the supporting surface for record files with practically no interruption in the work at hand.

Another object of the invention is to provide a device readily adapted for mounting on a general utility work table of a type commonly used in many offices.

A further object is to provide a device having a counterbalanced parallel linkage system by means of which the supporting platform may easily be shifted upwardly and downwardly with a comparatively heavy load of record files.

2

A still further object of the invention is to provide a device adaptable for use in an enclosed cabinet stand whereby records may be made readily accessible from a place of concealment as desired and also may be provided with an individual permanent or semi-permanent depository.

Other objects and advantages of the invention will be seen from the following description and accompanying drawings.

10 In the drawings:

Fig. 1 is a side elevation with various parts in section of a work stand with the new device mounted on the stand and supporting a record file tray in elevated position;

15 Figs. 2 and 3 are similar views of the device in intermediate and lowered positions;

Fig. 4 is a sectional view on line 4—4 of Fig. 1;

Fig. 5 is a side view of a modified construction of the device as adapted for a cabinet stand apparatus and illustrated in elevated position;

20 Fig. 6 is a section of the cabinet stand of Fig. 5 with the device in lowered position and a lid covering the cabinet top; and

Fig. 7 is a perspective view showing a removable tray clip as used on the platform of the device.

25 A general utility work stand or table of the type adapted for use with the new device is a familiar piece of office equipment. In the particular form of stand here shown in the drawings it is provided with a flat top 1 having a longitudinal recess 2. The side walls of the recess are cut away at their mid-portions to provide slots as at 3. A central opening 4 between the slots 3 is also provided in the bottom wall of the recess. The table serves with its particular form of recess to provide a convenient means for removably supporting a variety of work trays or heavy binders as may be nested on the table with portions thereof matching the recess.

30 The new platform device embodying the invention is mounted on the table top. It comprises a bottom support as lower plate 5, an upper support platform as plate 6, and a parallel linkage mechanism connecting the two plates. Centrally pivoted at the under side of the lower plate 5, as on a rivet 7, is a rotatable swivel lock bar or strap latch 8. When the device is placed on the top 1 with latch 8 suspended in the recess on the underside of plate 5 directly over the central opening 4, an operator may reach up from underneath to pivot the latch and swing its offset end portions into the slots 3 (Figs. 1 and 4). The plate 5 is thus releasably held locked on the work stand. This particular arrangement for

securing the device is a simplified and preferred construction although the bottom plate may be otherwise attached to a stand. The latch attachment shown utilizes the special utility of the stand and adds to its serviceability in being readily adapted to carry a vertically shiftable platform as well as a great many sizes of work trays or heavy binders each of which has a common formation of undersurface supporting means for nesting relation between the sidewalls of the 10 recess.

The top 1 of the work stand is itself vertically adjustable by means of telescoping leg members 9 and 10. A series of holes 11 in the legs permit their relative positioning by bolts as at 12. A bracing shelf 13 and swivel casters 14 complete the stand assembly.

It will be seen from a comparison of Figs. 1, 2, and 3 that the upper plate or platform 6 of the new device may be shifted from a lowered position, resting on the lower plate 5, to an elevated position vertically spaced from the lower plate and held parallel thereto at all times by the linkage mechanism connecting the two plates.

Parallel links 15 and 16, with a toggle joint associated with at least one of the links, form the connecting structure at the sides of the plates. The links 15 and 16 are pivoted at their upper ends to depending ears 17 and 18 of transverse straps 19 fixed on the underside of the upper plate platform 6 (Fig. 4). Intermediate the ends of links 15 short toggle links 20 (pivoted at one end as to an ear 21 of a transverse strap 22 fixed on lower plate 5) are pivotally connected as at 23 to form a toggle joint or knee with link 15. The lower ends of links 15 extending beyond the knee are pivotally mounted on two complementary guide members as slide bars 24 located at opposite side edges of the lower plate 5. Bars 24 are provided with roller wheels 25 at each end thereof, the wheels being held in runways formed by upstanding flanged sides 26 of plate 5 (see Fig. 4). The axles of the wheels provide the pivotal attachment of links 15 to the bars.

The parallel links 16 are similarly connected to the slide bars 24 of plate 5. Transverse straps 27 and 28 may be mounted for structural rigidity between the laterally aligned pairs of links 15 and 16 respectively. A connecting bar 29 joins the lower ends of links 15 and the axles of wheels 25 adjacent plate 5. A tension spring 30 is hooked at one end to bar 29 and its other end to plate 5 to urge the links 15 as shown towards an in-line position of the toggle joint members.

When platform 6 is in its lower position (Fig. 3) the links and the slide bars of the device lie at each side of plate 5 in a straight line collapsed position. The portion of link 15 forming a toggle joint with link 20 lies in adjacent relation with link 20. At their lower portions links 15 (Fig. 4) are offset outwardly to provide clearance for a nesting relationship. The spring 30 is here under its greatest tension.

By lifting platform 6, an operator may cause the same to swing upwardly of plate 5 and the toggle linkage to unfold (Fig. 2), the bars 24 sliding longitudinally in the tracks of plate 5. As the platform 6 is moved upwardly it is shifted lengthwise in an arcuate path according to the movement of the parallel linkage system. Links 15 and 16 are carried to a vertical perpendicular position between plates 5 and 6 and slightly beyond to an oppositely angled condition as shown by Fig. 1. In this position the guide bars 24 come to rest with the wheels 25 against stop lugs

31 attached to the flanged sides 26 of plate 5. Thus, further movement of the toggle joint to an in-line position and the upper plate 6 to a relatively lower position is blocked. In this condition, the platform is held in its elevated position of Fig. 1 by the weight of the load on the angled links and endwise pressure of bars 24 against lugs 31. Spring 30 is also exerting tension to maintain the platform in this position.

When platform 6 is in a lowered position (Fig. 3), the links are locked against the action of the spring. The toggle joint is folded at the knee and set in a straight line. The force of the spring is against longitudinally aligned pivots 23, 13 and 21.

The mechanism includes the spring counterbalancing means to assist in carriage of a load on the platform plate 6 in raising and lowering the same. The spring 30 is at all times under tension overlying bottom plate 5. It is hooked at one end to the bar 29 and anchored at the other end by a hook in the bottom plate 5 between stop lugs 31. It will be clear that on initially lifting platform 6 the spring tends to draw the lower ends of links 15 around the rising toggle joint pivot of knee 23. The slideable bars permit a rotative movement of links 15 around the knee and the action of the spring tends to "float" a heavy load on the platform 6 to its upward position. In the reverse operation, on lowering the platform, the spring will counterbalance a heavy load and act to resist a too rapid descent of the platform against plate 5.

Platform 6 is provided with upturned flanges 32 and 33 at its side and end edges respectively. These flanges assist in seating and holding record file trays on the platform surface such as a tray 34 illustrated by the drawings. Tray 34 is a known type of machine posting tray now in commercial use and is provided with cornered end walls 35 having open sides. Drop bars 36 are pivoted at the sides for swinging laterally and permitting individual cards of a stack 37 to be offset for better visibility and handling. Carrying handle openings 38 are also provided centrally in each end wall of the tray 34.

Platform 6 as shown is additionally fitted with holding clips 39 and 40 for convenience in mounting a tray in the assembly. Clip 39 at the left in the drawings may be permanently fixed to platform 6 with its top hook portion overlying that end. Clip 40 at the other end may be removable. It will be clear that in fitting tray 34 on the platform the tray may be tilted to hook the top of clip 39 in the adjacent handle opening 38 and the tray then rested on the platform. The removable clip 40 is then fitted on the other end. Clip 40 is of spring metal and has a lower offset portion with an upstanding tongue 41 (Fig. 7) fitting into a slot in the underside of platform 6. The upper hooked portion is first inserted into the handle opening 38 and the offset tongue is then swung and snapped into place in the slot. To remove the clip the tongue is sprung from its slot by pressure on the rounded top hook portion which flexes the metal against the lower edge of the handle opening 38 and permits withdrawal of the clip. Thus the tray 34 may be secured against removal and can be handled to raise and lower the platform 6.

The assembly as described provides a sturdy and rugged unit for use in manipulating heavy record files. It will be clear that the toggle jointed parallel linkage mechanism with its spring balanced tension may be modified in some re-

spects while preserving the advantages of the device as disclosed by Figs. 1-4. One such modification is illustrated by Figs. 5 and 6 which show a platform device as used in a "safe" or enclosed cabinet type of stand.

In this embodiment two parallel links 45 and two short links 46 are provided for the elevating mechanism. It will be seen that the slide bar 47 for the lower ends of the links is mounted on wheels in a track of a lower support plate 48 as in Figs. 1 to 4. The device is entirely enclosed in either position of adjustment by cabinet walls 49 and 50. In its upper position (Fig. 5) the stop against an in-line position of the toggle joint is provided by abutment of the platform 51 against the cabinet wall 50. In this example the latch mechanism and counterbalancing spring have been omitted. The device rests on the floor 52 of the cabinet or the lower support may be an integral part of the cabinet itself. A hinged cover 53 is provided to conceal and lock the file contents when in lowered position.

In the form of Figs. 5 and 6 the device has special utility in providing a greatly simplified construction for an enclosed cabinet type of file. The walls of the cabinet may be of fire proof construction for overnight and other temporary storage. The desirability of this type of office equipment is widely recognized for the permanent or semi-permanent deposit of file records. Confidential files can be immediately concealed and/or made available as desired and without elaborate precautions for handling.

Having described my invention, I claim:

A vertically shiftable platform device for record file holding equipment and the like comprising a lower and an upper support, parallel links between said supports and mechanism associated with the links for guiding and supporting said upper support from superimposed collapsed position to superimposed vertically spaced position in a path substantially perpendicular to the plane of said lower support, and spring means yieldably tensioned to maintain said upper support in either of said positions, said upper support having depending spaced pivotal connections with

corresponding ends of said parallel links, longitudinally slideable members carried by said lower support having spaced pivotal connections receiving the other ends of said parallel links, 5 toggle link straps pivoted to said lower support in the plane of said pivotal connections of the parallel links to said slideable means and offset therefrom, the other ends of said straps being attached in fixed pivotal relation with adjacent 10 parallel links at central portions thereof, said parallel links being rotatable around said strap ends, the lifting of said upper support above the lower support being guided by said straps with said slideable members moving longitudinally of said lower support, a stop for said slideable members at the end of the support, said straps with further movement of said members restricted by the stop holding the parallel links against further 15 rotative movement in the same direction and in an over the center relation between the supports, said spring means including a spring connected between said lower support and said slideable members and constantly urging the latter towards said stop with the centrally pivoted parallel links on the members being biased in the direction of further rotation around said strap ends, said parallel links, slideable members, and straps in collapsed position between said supports being in parallel relation and the pivotal connections therebetween in an in line condition, the 20 tension of said spring on said slideable means tending to maintain said in line position of said pivotal connections.

FRANK STANLEY SCHADE.
